Primary Examiner — Darlington Ly(74) *Attorney, Agent, or Firm* — McAndrews, Held & Malloy, Ltd.(57) **CLAIM**

The ornamental design for a vacuum break twist tap, as shown and described.

DESCRIPTION

FIG. 1 is a front perspective view of a vacuum break twist tap showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective cross-sectional view thereof. The dashed broken lines in the figures illustrate portions of the vacuum break twist tap that form no part of the claimed design.

1 Claim, 5 Drawing Sheets(56)
